UNITED STATES PATENT OFFICE.

FREDRICK R. BUTTERS, OF SYRACUSE, NEW YORK, ASSIGNOR TO SYRACUSE HEATER COMPANY, OF ADAMS, NEW YORK, A CORPORATION OF NEW YORK.

HEATER.

1,234,283.

Specification of Letters Patent.

Patented July 24, 1917.

Application filed March 30, 1915, Serial No. 18,176. Renewed May 4, 1917. Serial No. 166,493.

To all whom it may concern:

Be it known that I, FREDRICK R. BUTTERS, a citizen of the United States, and a resident of Syracuse, in the county of Onondaga, in the State of New York, have invented new and useful Improvements in Heaters, of which the following, taken in connection with the accompanying drawings, is a full, clear, and exact description.

10 This invention relates to certain improvements in heaters, such as furnaces for house heating purposes, and refers more particularly to means for supplying atmospheric air to the combustion chamber for consuming the gas-laden products of combustion, and thereby increasing the efficiency and fuel economy of the heater.

15 The main object is to provide simple means for supplying a continuous current 20 of highly heated atmospheric air directly to and uniformly over and upon the surface of the fuel so as to more effectively consume the gaseous and smoke products of combustion, and thereby obtain a greater 25 heat efficiency from a given quantity of fuel.

Another object is to cause the inflowing 30 atmospheric air to travel in tortuous paths in and around the fire pot so that it may be distributed over the surface of the fuel in 35 a highly heated condition to not only accelerate combustion of the gases and fuel, but also to consume the smoke products from the surface of the fuel.

Other objects and uses will be brought out 35 in the following description.

In the drawings—

Figure 1 is a vertical sectional view partly in elevation of a furnace, showing my improved means for feeding the heated air to 40 the combustion chamber.

Fig. 2 is a perspective view, partly in section, of the detached air ring forming a part 45 of the combustion chamber and the inlet and outlet air conduits leading thereto and therefrom.

Fig. 3 is a perspective view of a portion 50 of the heating drum surrounding the combustion chamber, showing the perforations through which the air is delivered into said combustion chamber.

The heater may be of any construction provided with a fire pot —1— having a combustion chamber —2—, a fuel inlet —3—

and a smoke outlet —4—, the furnace shown being provided with an ash box —5—, an 55 air chamber —6— surrounding the fire pot —1— and drum —2— and communicating at the top with a delivery chamber —7— having outlets —8— for receiving pipes which may extend to different parts of the 60 building for supplying heated air thereto.

The main feature of my invention, however, consists of a hollow ring —9— surrounding and forming a section of the fire box —1— and in providing the interior of 65 said ring with baffle plates —10— and —11— projecting from opposite walls (preferably from the bottom and top) part way across the intervening space and in staggered relation uniform distances apart 70 so as to cause the inflowing air to travel in tortuous paths therethrough.

This ring is provided in its front side with an air inlet pipe —12— leading radially through the front side of the furnace casing 75 or jacket —13— below the fuel inlet —3— to permit the entrance of atmospheric air therethrough and into the hollow ring —9—.

Leading from the rear end of this ring is an outlet pipe —14— which extends upwardly to a point just above the upper end of the fire pot where it is provided with an enlarged hollow head or distributing chamber —15— surrounding a perforated portion —16— of the heating drum as 85 —2'—, the hollow head or distributing chamber —15— being secured by bolts or rivets to the periphery of said shell around the margin of the apertured portion —16— so as to form an air-tight joint therewith. 90

The fire pot —1— is preferably made in annular sections arranged end to end of which the air ring —9— constitutes the intermediate section so that the inner wall of the ring is in direct contact with the fuel, 95 thereby causing the air traveling through the ring —9— to be heated to a high degree, in which condition it is delivered to the combustion chamber directly over and upon the fuel, the inlet pipe —12— and outlet 100 pipe —14— being preferably made separate from the ring to enable the latter to be more conveniently assembled as a member of the fire pot when the parts of the heater are being set up, the front and rear portions of 105 the ring —9— being provided with hollow

nipples to which the pipes —12— and —14— are attached after the ring is placed in proper position in the fire pot.

What I claim is:

5 In a heater of the character described, the combination of a fire pot having a hollow section provided with a cold air inlet and a hot air outlet, a heat-radiating drum mounted on the fire pot and provided with 10 a fuel inlet and a smoke outlet and also having a relatively small area of one side there-

of perforated, a pipe leading from the air inlet to the atmosphere, and a separate pipe leading from the hot air outlet and covering the perforated area of the drum to conduct 15 the heated air into the interior thereof.

In witness whereof I have hereunto set my hand this 6th day of March, 1915.

FREDRICK R. BUTTERS.

Witnesses:

H. E. CHASE,

ALICE M. CANNON.
